UNITED STATES PATENT OFFICE.

LARS WALDEMAR LAURÉN, OF OREBRO, SWEDEN, ASSIGNOR OF ONE-HALF TO ERIK
EMANUEL ERICSSON, OF ROSTA, OREBRO, SWEDEN.

FOLDING BUCKET OR THE LIKE.

Application filed March 10, 1920. Serial No. 364,695.

To all whom it may concern:

Be it known that I, LARS WALDEMAR LAURÉN, a subject of the King of Sweden, residing at Rudbecksgatan 30, Orebro, in the 5 Kingdom of Sweden, have invented certain new and useful Improvements in Folding Buckets or the like, of which the following is a specification.

This invention relates to folding-buckets 10 or the like made of water-proof fabric or similar material and surrounded by a coiled spring which keeps the bucket in an extended position. According to this invention pins and hooks are provided at the bottom and 15 upper rims of the bucket respectively and adapted to keep the bucket in foldable position, the said pins and hooks being so located with relation to one another, that, when the bucket is in folded position, the said coiled 20 spring is subjected to torsion and adapted to keep the hook in engagement with the pins.

In the accompanying drawing Figs. 1 and 2 show, in side elevation and viewed from 25 two different sides, a bucket arranged in accordance with this invention.

The mantle 1 of the bucket, made of water-proof fabric, is fixed in any suitable manner to a rim provided on a bottom 2 of sheet 30 metal, and to a ring or rim 3. The lower-most coil of a coil-spring 5, which extends round the mantle 1, is located in a groove 4 provided in the bottom 2, and the top coil of the spring is located in a groove provided in 35 the ring 3. The ends of the wire 5 may be bent around the next coil, as shown in the top part of Fig. 1. The coil spring may, however, be fixed in any other suitable manner. At the bottom 2 two pins 6, located opposite to one another are provided, the said pins consisting preferably of the ends of a rod, located under the bottom and extending through the bottom flange. To the rim 3 two hooks 7 are fixed adapted to engage the said 40 pins 6, while the bucket is in folded position, and thus keep the bucket in the said position. The pins 6 are so located with relation to the hooks 7, that, as the bucket is being folded, the bottom and the rim 3 must 45 be rotated relatively to one another in the directions indicated by the arrows so that the coil-spring 1 is subjected to torsion and after the pins 6 have been placed in the hook 7, tends to keep the pins in engagement with

the hooks. Thus, the security of the hooks 55 not being unintentionally disengaged from the pins is increased. As the pins 6 are being placed in the hooks, the pins may slide on the lower edge of the rim 3. Preferably, the pins are provided with notches, which the 60 hooks 7 engage and by which the hooks are held laterally. When the bucket is in unfolded position, it is supported by the coil-spring 5, which is made of sufficiently rigid wire, so that the bucket does not shrink. The 65 bottom 2 is so arranged, that the same together with the lower coils of the coil-spring enter the rim 3, when the bucket is brought into its folded position.

In connection with the foregoing it is to 70 be noted that the groove in the rim 3 and the groove 4 are preferably provided by forming exterior flanges on the rim 3 and the bottom 2. In addition it is to be noted that the hooks are offset medially of their ends 75 while the inner ends are provided with openings for receiving the looped ends of a bail or the like 7'.

Buckets arranged in accordance with the 80 present invention may be used in boats, automobiles, as fire-implement and in any case in which it is of importance that the buckets when stowed in take up a minimum of space.

I claim:

1. A folding bucket comprising a bottom, 85 a top rim, a water-proof flexible body portion connected to the bottom and the rim, a coiled spring surrounding the body and having its respective ends bearing against the bottom and the top rim and normally holding the bucket extended, pins projecting from 90 opposite points of the bottom, a bail and elements pivoted at opposite points exteriorly of the rim and having their upper ends shaped to accommodate the ends of the bail 95 and their lower ends shaped to form hooks for engagement with the pins subsequent to the compressing of the spring whereby to hold the bucket in a folded position.

2. A folding bucket comprising a bottom, 100 an external annular flange surrounding the outer edge of the bottom and forming a groove, a top rim formed with an exterior annular groove, a water proof flexible body portion connected to the bottom and the rim, 105 a coiled spring surrounding the body and having its respective end coils seated in the grooves, notched pins projecting from oppo-

site points of the bottom, hooks pivoted at opposite points of the rim exteriorly thereof for releasing engagement with notched pins and having their inner end portions offset and 5 provided with openings and a bail having its looped ends engageable with the openings in the inner ends of the hooks.

In testimony whereof I have affixed my signature in the presence of two witnesses:

LARS WALDEMAR LAURÉN.

Witnesses:

ROBERT APELGREN,
INEZ SVENSEN.
